UNITED STATES PATENT OFFICE.

CHARLES SONNEBORN, OF WEST PITTSBURG, PENNSYLVANIA, ASSIGNOR TO PRESSED METAL RADIATOR COMPANY, OF PITTSBURGH, PENNSYLVANIA, A CORPORATION OF PENNSYLVANIA.

MACHINE FOR CONNECTING RADIATOR-SECTIONS.

1,158,868.

Specification of Letters Patent.

Patented Nov. 2, 1915.

Application filed April 18, 1914. Serial No. 832,732.

To all whom it may concern:

Be it known that I, CHARLES SONNEBORN, a resident of West Pittsburg, in the county of Lawrence and State of Pennsylvania, have invented a new and useful Improvement in Machines for Connecting Radiator-Sections, of which the following is a specification.

This invention relates to a machine for connecting or assembling radiator sections, and particularly the sections of sheet metal radiators.

The object of the invention is to provide a simple and effective machine whereby any number of radiator sections may be secured together expeditiously, which firmly supports the sections while being assembled, and which machine is adjustable in various ways to accommodate sections of various sizes and shapes.

The invention comprises the construction and arrangement of parts hereinafter described and claimed.

In the drawings Figure 1 represents a plan view of one form of machine embodying the invention, the expanding devices being omitted; Fig. 2 is a front elevation thereof; Fig. 3 is an end elevation; Fig. 4 is an elevation of the upper end portion of one of the columns or standards, and showing an expanding device thereon; and Fig. 5 is a sectional elevation on the line 5—5, Fig. 3.

The machine shown in the drawings comprises a base or bed plate 1 which rests on the floor or upon a suitable support, and which in turn carries two columns or standards, marked respectively 2 and 3, which are hollow cast iron members, and each of which is provided with a level flat top 4 to receive an expanding machine 5, which assembles the radiator sections as hereinafter more fully described.

The front face of each of the standards 2 and 3 is provided with suitable apertures 6 for receiving bolts 7 for securing thereto upper and lower brackets 8 and 9, which project out from the front of the machine and support the radiator sections while being assembled.

The upper brackets 8 are provided with journal boxes 10 for two longitudinally extending parallel shafts 11, and the lower brackets 9 are provided with brackets 12 in which are rigidly secured studs 13. Shafts 11 are provided at each end between the brackets 8 with sprocket wheels or members 14 fixed to rotate with said shafts, while each of the studs 13 is provided with a corresponding sprocket wheel 14a loosely journaled thereon. The corresponding upper and lower sprockets are connected to rotate together by means of chains 15 passing over said sprockets, there being four such chains in all. Each chain comprises links of the form shown in Fig. 3, the contiguous ends of adjacent links being cut away to provide sockets or spaces 16 therebetween for receiving the edges of the radiator sections and for supporting said sections while being assembled and for carrying them through the machine. The chain links are of course of a length corresponding to the thickness of the radiator sections and a separate set of chains and sprockets is provided for each different thickness of section, as will be readily understood.

The chains 15 turn in unison, but the front shaft 11 rotates in one direction and the back shaft in the other, so that the inner strands of the chains 15 move in the same direction and, as the sprockets are of the same size, at the same rate of speed. The two longitudinal shafts are driven by means of a single transverse shaft 17, having an operating handle 17a, and journaled in brackets 18 attached to one of the upper brackets 8, and which shaft is provided with two worms 19, provided respectively with right and left-hand threads, and which drive worm gears 20 on the two shafts 11.

The strands of the several chains are held rigidly during the assembling operation by backing and spacing members 21, which fill the space between the two strands of each chain, and which comprise two plates held together by bolts 22 and at their upper ends cut away and fitting in grooves 23 in the sprocket member.

In use of the machine a radiator section is placed in the machine from above with its side edges fitting in the sockets or notches 16 between the ends of adjacent links of the 5 chains, and shaft 17 is then rotated to move said section downwardly. A second radiator section is applied to the next set of sockets 16 in the same manner, shaft 17 being then rotated until said section moves 10 down to the position shown at *a*, Fig. 2. The tool spindles 24 of the expanding machines lie directly over the openings through the adjoining bosses of the radiator sections, and said tool spindles are moved down- 15 wardly into engagement with said sections to roll the edge of the metal of one section around the edge of the other and form a beaded joint. Any suitable expanding tool or device may be used for this step, such as 20 the device shown in my Patent No. 1,120,100, dated Dec. 8, 1914, for expanding head. After the two radiator sections are secured 25 together another section is applied to the machine and shaft 17 is rotated to move the sections downwardly one more step, and the third section is secured to the second in the same manner before described, the operation continuing in this manner step by step until a sufficient number of sections have 30 been secured together to form a complete radiator. The radiator is discharged from the bottom of the machine into a pit, being released from the chain step by step as it moves downwardly. When sufficient radi- 35 ator sections have been secured together to make a complete radiator the next set of sockets or spaces 16 in the four chains is skipped and the next radiator to be assembled is begun on the second set of said 40 notches following the last one previously used. In this manner the operation can be fairly continuous, as the radiator sections are applied at the top of the machine, are assembled in the machine while held between 45 the several chains and are discharged at the bottom of the machine. The four chains form efficient supports for the side edges of the radiator sections and are rigidly held against lateral displacement by the backing 50 members 21, so that there is no give or lost motion.

The radiator sections at their ends are guided and held in proper registering relation with each other by any suitable means, 55 such as the rails 25, shown as channel members having their flanges turned inwardly and along the edge of which the radiator sections ride, and which channel members are held on the ends of studs 26 adjustable in 60 openings in the brackets 8 and 9 and held in adjusted position by set screws 27.

To adjust the machine for accommodating radiator sections of different lengths the two

standards or columns 2 and 3, and the parts carried thereby, are adjustable lengthwise 65 on the bed or support 1. Both of the standards are shown as adjustable, although only one thereof need be adjusted. As shown, the base or support 1 is provided with ways 30 along which the columns are movable. 70 Both of said columns may be held in any ad- justed position in said ways by suitable set screws 31 threaded through the base 1 and arranged to engage the lower end of said column. Column 2 is usually fixed or 75 clamped in one position and is not adjusted except under unusual circumstances, as for some special or unusual size of radiator. Column 3 is the adjustable column and is provided with suitable means for readily 80 moving it, such as a nut 32 carried in its base and which coöperates with a threaded shaft 23 journaled in a boss 34 in the bed 1, and which can be rotated by any suitable tool applied to the non-circular end 35 there- 85 of. When the column 3 is adjusted length- wise on the bed it carries with it the upper and lower brackets 8 and 9 secured thereto. Also the journal boxes 10 for the shafts 11 are provided with locking members 36 hav- 90 ing their end portions bent downwardly into annular grooves 37 in the sprocket members 14, so that said sprocket members, which are splined to the shaft 11, are adjusted along 95 said shaft with the column 3. With the ar- rangement described the machine can be readily adapted for assembling sections of different lengths by merely rotating the shaft 33, which carries all of the mechanism at one end of the machine, including the ex- 100 panding head 5, toward the other end of the machine.

The machine is also arranged for accom- modating radiator sections of different widths, and for this purpose the journal 105 boxes 10, the brackets 18 in which the shaft 17 is journaled, and the stud supports or brackets 12 are adjustable lengthwise on the brackets 8 and 9, which are shown as pro- 110 vided with T-slots 40 for receiving the head- ed ends of the bolts 41 for securing said members to the brackets. It will also be understood that the worms 19 are splined to shaft 17, so that they can move longitudi- 115 nally thereon. The expanding machines 5 are preferably rigidly mounted upon the platforms 4 of the standards 2 and 3, and their tool spindles 24 are not adjustable lat- erally of the machine. The joints between 120 adjacent radiator sections are always placed midway between the side edges of said sec- tions, so that to accommodate sections of dif- 125 ferent widths both of the shafts 11 and the side chains at both edges of the radiator section must be adjusted to accommodate sec- tions of a different width. Consequently,

when the machine is to be adapted for a narrower section the two sets of chains are adjusted toward each other, while when a wider section is to be accommodated they 5 are adjusted farther apart.

What I claim is:—

1. A machine for assembling radiator sections, comprising means for supporting and holding a plurality of radiator sections 10 perimposed upon each other in parallel planes, and means for feeding the sections through the machine in a direction perpendicular to said planes.
2. A machine for assembling radiator sections, comprising means arranged to engage the edges of the radiator sections and hold them in registering relation, and means arranged to act upon said sections between their edges for assembling the same.
3. A machine for assembling radiator sections, comprising a series of movable radiator section holding members, and means co-operating therewith and movable in the same direction for assembling said sections.
4. A machine for assembling radiator sections, comprising means for supporting and holding the radiator sections in registering relation, and movable means for assembling said sections, said holding means being movable in the line of movement of the assembling means and adapted to receive successive radiator sections and pass them through the machine.
5. A machine for assembling radiator sections, comprising a plurality of radiator holding means movable in line with each other in one direction, and assembling means movable in the same direction for securing the radiator sections together.
6. A machine for assembling radiator sections, comprising endless flexible members arranged to engage successive radiator sections and hold them in registering relation, and means for assembling said sections.
7. A machine for assembling radiator sections, comprising endless flexible members arranged to engage the edges of the radiator sections and hold them in registering relation, means for moving said members to pass the radiator sections through the machine, and means for securing successive sections to each other.
8. A machine for assembling radiator sections, comprising endless flexible members 55 arranged to engage the opposite edges of the radiator sections and hold them in registering relation, said members being adjustable toward and from each other to accommodate different sizes of radiator sections, and means co-operating therewith for securing the sections together.
9. In a machine for assembling radiator sections, the combination of a plurality of

endless flexible members arranged to engage the opposite side edges of the radiator sections and hold them in registering relation, said members being adjustable toward and from each other, and some of said members being adjustable lengthwise of the radiator section to thereby hold various sizes 70 of radiator sections.

10. In a machine for holding radiator sections, while being assembled, the combination of endless flexible members arranged to engage opposite edges of the radiator sections and hold them in registering relation, rotatable means supporting said members, and means for moving said members in unison to pass the radiator sections through the machine.

11. A machine for assembling radiator sections, comprising a frame, standards on said frame and carrying devices for securing radiator sections together, and means also carried by said standards for supporting and holding the radiator sections in registering relation.

12. A machine for assembling radiator sections, comprising a frame, standards on said frame and carrying devices for securing radiator sections together, means also carried by said standards for supporting and holding the radiator sections in registering relation, and means for adjusting said standards relatively to each other.

13. A machine for assembling radiator sections, comprising a pair of standards adjustable toward and from each other and each supporting a device for securing radiator sections together, brackets on said standards, means carried by said brackets and arranged to engage the side edges of radiator sections and hold them in registering relation while being assembled and means for adjusting said holding means toward and from each other to accommodate sections of different widths.

14. A machine for assembling radiator sections, comprising a pair of standards, brackets thereon, shafts carried by said brackets and adjustable toward and from each other, sprockets carried by said shafts and flexible means traveling over said sprockets and arranged to support and hold radiator sections in registering relation.

15. A machine for assembling radiator sections, comprising a pair of standards, brackets thereon, shafts carried by said brackets and adjustable toward and from each other, sprockets carried by said shafts, 120 flexible members traveling over said sprockets and arranged to support and hold radiator sections in registering relation, and means for rotating said shafts in unison in opposite directions.

16. A machine for assembling radiator

sections, comprising a pair of standards, brackets thereon, shafts carried by said brackets and adjustable toward and from each other, sprockets carried by said shafts, flexible members traveling over said sprockets and arranged to support and hold radiator sections in registering relation, and means for rotating said shafts in unison in opposite directions, said standards being

adjustable longitudinally of said shafts toward and from each other.

In testimony whereof, I have hereunto set my hand.

CHARLES SONNEBORN.
